UTILITY BOARD

David C. Braden, Indianapolis, Ind.

Application March 6, 1944, Serial No. 525,154

12 Claims. (Cl. 155—127)

The present invention relates to a utility board installation, and the primary object thereof is to provide a work board, for supporting work, books, meals, and the like for a sedentary invalid, together with means for suitably securing the board in place upon a chair, either stationary or wheeled. Further objects of the invention will appear as the description proceeds.

To the accomplishment of the above and related objects, my invention may be embodied in the form illustrated in the accompanying drawing, attention being called to the fact, however, that the drawing is illustrative only, and that change may be made in the specific construction illustrated and described, so long as the scope of the appended claims is not violated.

Fig. 1 is a fragmentary perspective view of a wheel chair with my invention installed thereon;

Fig. 2 is a fragmentary enlarged view of one of my board-retaining brackets secured to an arm of a chair when the board is not in use;

Fig. 3 is a view similar to Fig. 2, but showing a fragment of the board in place, with the bracket retainingly associated therewith; and

Fig. 4 is a transverse sectional view taken substantially upon the line 4—4 of Fig. 3, and looking in the direction of the arrows.

It is recognized that I am by no means the first to have produced a work-supporting tray or board adapted to be supported upon the arms of a chair. But I believe that I have cured, by the present invention, the operational and structural defects inherent in previously known devices intended for the general purpose for which the present invention is designed. By the present invention, I provide a board which is flat upon its upper and lower surfaces; which may be readily removed from, or associated with, the chair; which provides a maximum of work space without interfering with movement of the chair; which provides support for the patient's arms when the board is used for writing; which may be safely laid upon any flat surface when not in use without interference from brackets, rails, or the like upon the bottom surface of the board; which may be stacked with others like it when not in use; and which may be inexpensively produced in large numbers.

For purposes of illustration, I have shown my board, in Fig. 1, associated with a wheel chair indicated generally by the reference numeral 10 and having standard, parallel, horizontal arm rests 11 and 12. With each of the arm rests is associated a bracket, indicated generally by the reference numeral 13, and manipulable to en-

gage portions of the board 14 adapted to be supported upon the upper surfaces of the arm rests 11 and 12. The board 14 is formed, at its rear edge, with a cutout portion 15 to accommodate the body of the patient; and its outer edges, near the rearmost portion of the board, are cut away, as at 16 and 17, to accommodate the arms of the patient when he desires to handle the wheels 18 of the chair. Thus, although the width of the board 14 toward its forward portion is substantially equal to the maximum width of the chair 10 including the wheels 18 and their axles, the rearward portion of the board has a width only equal to the distance between the outer edges of the arm rests 11 and 12. Because the width of the forward portion of the board 14 does not exceed the overall width of the chair 10, the board will not interfere with any movement of the chair. Thus, for instance, the board 14, when installed on the chair, will pass through any door with a width enough to accommodate the chair itself.

The brackets 13 are identical, and one of them is shown in detail in Figs. 2, 3, and 4.

Each bracket comprises a vertical leg 19, formed with a pair of parallel, spaced, vertically elongated slots 20 and 21. Screws 22 and 23 pass through the slots 20 and 21, respectively, and are projected into the outer vertical edge of the arm rest 11 or 12. The screws 22 and 23 are set up tightly enough to engage the bracket leg 19 frictionally, but are so set that the bracket 13 may be moved vertically by pressure exerted upon the lower edge thereof or upon the upper edge thereof. The lowermost extremity of the leg 19 is turned inwardly and upwardly as at 24 to provide a smooth, curved surface 25 at the lower end of the leg 19 for engagement by the patient's fingers to shift the bracket upwardly.

Each bracket 13 also comprises a horizontal leg 26 projecting inwardly to overlie the upper surface 28 of the arm rest 11 or 12 with which it is associated. The bracket leg 26 is formed with a perforation 27 for a purpose later to be described.

The slots 20 and 21 are so proportioned that the screws 22 and 23 are located substantially in their upper ends when the lower surface of the bracket leg 26 is in engagement with the upper surface 28 of the associated arm rest; and that the screws 22 and 23 are substantially in the lower ends of said slots when the lower surface of the bracket leg 26 is spaced from the arm rest surface 28 a distance substantially equal to the thickness of the reduced portion 29 or 30 of the board 14. Thus, when the board 14 is not in

place, the brackets are depressed to the position shown in Fig. 2, wherein the bracket legs 26 are not in a position to interfere with any movement of the patient. When it is desired to associate the board 14 with the chair, upward pressure is exerted against the lower ends 25 of the brackets 13 and they are shifted into the position illustrated in Figs. 1, 3, and 4. The board 14 is then slid into the position illustrated in Fig. 1, wherein the portions 29, 30 thereof are supported upon the arm rests 11 and 12, and engaged between the vertical legs 19 of the two brackets 13, and between the horizontal legs 26 thereof and the arm rests 11 and 12.

The portions 29 and 30 of the board 14 are preferably formed with a plurality of longitudinally spaced perforations 31; and preferably the arm rests 11 and 12 are formed with sockets 33 registering with the perforations 27 of the bracket legs 26. The board 14 is shifted into a position in which one or another of the perforations 31 of each portion 29 and 30 registers with the perforation 27 of the associated bracket. Such perforation 31 will, of course, register also with the socket 33 and the associated arm 11 or 12. A pin 32, which is preferably tied or fastened to its associated arm 11 or 12 by a string or chain or the like, may now be dropped through the perforation 27 and the associated board perforation 31, and into the socket 33, to hold the board 14 against movement relative to the arm rests and brackets.

Alternatively, the sockets 33 may be eliminated, and the bores 31 of the board portions 29 and 30 may be either perforations or sockets, in which case the pins 32 will cooperate only with the perforations 27 and the holes 31 in the board portions 29 and 30. It will be appreciated, of course, that the pins 32 and holes 27, 31, 33 are not absolutely essential to the use of the other parts of my invention, although they are a desirable feature in that they lend added stability to the assembly.

I claim as my invention:

1. The combination with a chair having horizontal arm rests, of two L-shaped brackets having their vertical stems slidably attached to the remote vertical surfaces of said arm rests, and vertically shiftable with respect thereto, and having their horizontal branches overhanging the horizontal surfaces of their respective arm rests, and a utility board having portions adapted to be supported upon said arm rests; said board portions, when so supported, being confined between said bracket stems and being further confined between said bracket branches and said arm rests.

2. The combination with a chair having horizontal arm rests, of bracket means carried by said arm rests and vertically shiftable with respect thereto, and a utility board having portions adapted to be supported upon said arm rests; said bracket means, when at their uppermost positions, overlying and engaging said board portions, and means cooperating with said bracket means and with said board portions for preventing relative movement between said board and said bracket means.

3. The combination with a chair having horizontal arm rests, of bracket means carried by said arm rests and vertically shiftable with respect thereto, and a utility board having portions adapted to be supported upon said arm rests, said bracket means, when at their uppermost positions, overlying and engaging said board portions, and means cooperating with said board portions

and with said arm rests for preventing relative movement between said board and said arm rests.

4. The combination with a chair having horizontal arm rests, of bracket means carried by said arm rests and vertically shiftable with respect thereto, and a utility board having portions adapted to be supported upon said arm rests, said bracket means, when at their uppermost positions, overlying and engaging said board portions, and means cooperating with said bracket means, said board portions, and said arm rests for holding said board against movement relative to said arm rests.

5. The combination with a chair having horizontal arm rests, of bracket means comprising an L-shaped member for each of said arm rests, each of said members including a vertical leg formed with a longitudinal slot, and a horizontal leg, means snugly received in said slot and projected into the outer vertical edge of the associated arm rest to secure its member vertically adjustably in place on said arm rest, with its horizontal leg overlying the top surface of said arm rest, and a utility board having portions insertable between the vertical legs of said members and between the horizontal legs thereof and said arm rests.

6. The combination with a chair having horizontal arm rests, of bracket means comprising an L-shaped member for each of said arm rests, each of said members including a vertical leg formed with a longitudinal slot, and a horizontal leg, means frictionally engaging said vertical leg, projected through said slot and into the outer vertical edge of the associated arm rest to secure its member vertically adjustably in place on said arm rest, with its horizontal leg overlying the top surface of said arm rest, the lower extremity of said vertical leg being bent inwardly and upwardly to provide a downwardly-facing rounded surface at the bottom of said leg, and a utility board having portions insertable between the vertical legs of said members and between the horizontal legs thereof and said arm rests.

7. The combination with a chair having horizontal arm rests, of bracket means comprising an L-shaped member for each of said arm rests, each of said members including a vertical leg formed with a longitudinal slot, and a horizontal leg formed with a perforation, means frictionally engaging said vertical leg, projected through said slot and into the outer vertical edge of the associated arm rest to secure its member vertically adjustably in place on said arm rest, with its horizontal leg overlying the top surface of said arm rest, a utility board having portions insertable between the vertical legs of said members and between the horizontal legs thereof and said arm rests, said portions being formed with sockets registerable with said bracket perforations, and pins insertable through said perforations and in said sockets to hold said board against movement relative to said brackets.

8. The combination with a chair having horizontal arm rests, of bracket means comprising an L-shaped member for each of said arm rests, each of said members including a vertical leg formed with a longitudinal slot, and a horizontal leg formed with a perforation, means frictionally engaging said vertical leg, projected through said slot and into the outer vertical edge of the associated arm rest to secure its member vertically adjustably in place on said arm rest, with its horizontal leg overlying the top surface of said arm rest, a utility board having portions insertable between the vertical legs of said members

and between the horizontal legs thereof and said arm rests, each of said board portions being formed with a plurality of spaced sockets selectively registrable with the perforations of one of said brackets, and a pin for each of said brackets insertable through its bracket perforation and into a registering board socket to hold said board against movement relative to said brackets.

9. The combination with a chair having horizontal arm rests, of bracket means comprising an L-shaped member for each of said arm rests, each of said members including a vertical leg formed with a longitudinal slot, and a horizontal leg formed with a perforation, means frictionally engaging said vertical leg, projected through said slot and into the outer vertical edge of the associated arm rest to secure its member vertically adjustably in place on said arm rest, with its horizontal leg overlying the top surface of said arm rest, each of said arm rests being formed in such top surface with a socket registering with the perforation in the horizontal leg of its associated bracket, a utility board having portions insertable between the vertical legs of said members and between the horizontal legs thereof and said arm rests, said portions being formed with perforations registrable with said bracket perforations and with said arm rest sockets, and pins insertable through said registering perforations and into said sockets to hold said board against movement relative to said arm rests and brackets.

10. The combination with a chair having horizontal arm rests, of bracket means comprising an L-shaped member for each of said arm rests, each of said members including a vertical leg formed with a longitudinal slot, and a horizontal leg formed with a perforation, means frictionally engaging said vertical leg, projected through said slot and into the outer vertical edge of the associated arm rest to secure its member vertically adjustably in place on said arm rest, with its horizontal leg overlying the top surface of said arm rest, each of said arm rests being formed in such top surface with a socket registering with the perforation in the horizontal leg of its associated bracket, a utility board having portions

insertable between the vertical legs of said members and between the horizontal legs thereof and said arm rests, each of said board portions being formed with a plurality of spaced perforations selectively registrable with the perforation of one of said brackets and with its registering arm rest socket, and a pin for each of said brackets insertable through its bracket perforation and a registering perforation in the associated board portion and into its arm rest socket to hold said board against movement relative to said arm rests and brackets.

11. For use with a chair having horizontal arm rests, and a utility board formed with portions adapted to be supported on said arm rests, a bracket for each of said arm rests and comprising a vertical leg and a horizontal leg, means cooperating with said vertical leg to secure the same to the outer edge of one of said arm rests for limited vertical movement with respect thereto and with said horizontal arm overlying the upper surface of said arm rest, said means limiting upward movement of said bracket to a position in which the lower surface of the horizontal leg thereof is spaced from the upper surface of its associated arm rest a distance substantially equal to the vertical thickness of said portion of said board adapted to be supported on said arm rest, and downward movement of said bracket being limited by engagement of its horizontal leg with said arm rest.

12. For use with a chair having horizontal arm rests, and a utility board formed with portions adapted to be supported on said arm rests, a pair of brackets adapted to be vertically adjustably secured to said arm rests to hold said board portions in position thereon, each of said brackets comprising a horizontal leg formed with a perforation therethrough, and a depending vertical leg formed with a pair of spaced parallel longitudinally-extending slots therethrough, the lowermost extremity of said vertical leg being turned upwardly to incline toward said horizontal leg to provide a rounded surface at the bottom of said vertical leg.

DAVID C. BRADEN.
